CLAIM

The ornamental design for a furniture leg, as shown and described.

DESCRIPTION

FIG. 1 is a front perspective view of a furniture leg showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front perspective view in an expanded state;

FIG. 10 is a rear perspective view in an expanded state; and,

FIG. 11 is a front perspective view showing the furniture leg in a position of use with environmental subject matter.

The broken lines in FIG. 11 depict environmental subject matter that form no part of the claimed design.
